ATTORNEYS.

UNITED STATES PATENT OFFICE.

ARTHUR LOW PATTERSON, OF ALBEMARLE, NORTH CAROLINA.

PRINTING DEVICE.

No. 874,790.

Specification of Letters Patent.

Patented Dec. 24, 1907.

Application filed May 10, 1907. Serial No. 372,887.

To all whom it may concern:

Be it known that I, ARTHUR LOW PATTERSON, a citizen of the United States, residing at Albemarle, in the county of Stanley and 5 State of North Carolina, have invented a new and useful Improvement in Label-Printing Devices, of which the following is a specification.

Labels for hosiery and many other similar 10 articles of merchandise are generally printed at the printing office with the wholesaler's name and trade-mark, but one or more blank spaces are left for the size and call numbers which, owing to the variations, are subsequently put on at the factory. It is difficult 15 to stamp these numbers neatly with an ordinary rubber stamp and often an order requires several cases to be numbered with different call numbers, and in such instances 20 it is necessary to count out the required number for each case.

My invention is designed to provide a printing device for use at the factory for the purpose of adding to the printed labels the 25 subsequent specific number and designations in a rapid, neat, accurate and convenient manner and at the same time counting out any desired number and announcing the completion of the batch by a bell signal. 30 The invention consists in the novel construction and arrangement of parts, which I will now proceed to describe with reference to the drawings, in which

Figure 1 is a perspective view of the entire 35 device resting on a table T. Fig. 2 is an enlarged plan view of the label holding portion of the device. Fig. 3 is a vertical section taken through line 3—3 of Fig. 2. Fig. 4 is a vertical section taken through the printing 40 and label holding mechanism. Fig. 5 is a sectional detail on line 5—5 of Fig. 2, and Fig. 6 is a section on line 6—6 of Fig. 1.

Referring to Fig. 1, A represents a sub base upon which is mounted a superposed 45 base B carrying a label holder, a printing device C, a counter D, and a bell E, combined with each other in a coactive relation.

An inking pad 16 is mounted on the base A and the printing device C is arranged between the ink pad and the label holder and is adapted, see Fig. 4, to be swung over to contact with the ink pad in one position, as shown in dotted lines, and then be swung over to and down upon the labels as shown 55 in full lines, to print the number or other impression thereon.

The label holder, see Figs. 1, 2 and 4, has its basic portion B adjustably connected to the main base A by a clamp bolt F whose shank goes through a hole in the main or sub base A and has in a recess in the lower surface of the base a large overlapping head or washer G, Fig. 4. This hole through the sub-base is made much larger than the bolt F in every direction, so as to give an adjustment in two directions, one longitudinally to the sub-base as seen in Fig. 4 and also another adjustment transversely to the sub-base as seen in Fig. 3. This adjustment permits the label holder to be adapted in position to the printing device C, so as to accommodate any size or shape of label.

The numeral 1 designates a stack of labels which as seen in Fig. 1, have already been printed at the printing office, but are yet to 75 receive the size or call numbers, or other designation, in the rectangular spaces y reserved for them and which it is the function of my invention to apply. These labels rest upon a base plate 23, Fig. 2, and are retained 80 in place by an adjustable overhanging lip 2 arranged at the end, an adjustable standing flange 4 forming a gage arranged at the side, a stationary overhanging lip 6 opposite the flange 4, and a press plate 7 pressing 85 upon the top end portions of the stack of labels, as shown in Fig. 1.

The adjustable end lip 2 is attached to a slotted shank portion 11 which, by means of a set screw 3, is fixed in place to any adjustment required by the length of the label.

The standing side gage 4 is, in like manner, attached to a slotted shank portion 12 which by means of a set screw 5 is fixed to any adjustment required by the width of the 95 label. The standing flange 4 is not exactly vertical, but leans slightly toward the printing devices, for the purpose hereafter described.

The press plate 7, which rests on top of the ends of the stack of labels 1, has an offset 8 against which lies the bent end of a spring 9 which tends to force the press plate down with an elastic pressure to clamp the labels at this end. This press plate is guided in its up and down movement by two pins 10, as seen in Figs. 3 and 5, which pins enter holes in the subjacent base and prevent the press plate from turning.

The printing device consists of a swinging 110 type carrier C mounted upon four links 14 which are pivoted at their upper ends to the

carriage and at their lower ends to a block 15, for a parallel motion of the carriage, which carrier as it swings between the two positions shown in Fig. 4, always maintains 5 a horizontal position. The carrier of the printing device is slotted, as seen at 13 in Figs. 1 and 4, and in this slot is adjustably secured the screw threaded stem of the type bed X whose position is fixed by the screw 10 knob x on top of the carriage. By means of this screw knob and slot 13 the position of the type bed may be adjusted sidewise to the plane of movement, or be entirely turned around or inverted to accommodate the form 15 of the label and the position of the space thereon which is to receive the printed number.

Pivoted to one of the links 14 is a horizontal rod 17 whose opposite end is bent and 20 made to engage the teeth of a ratchet wheel 18, being held down to engagement with the ratchet wheel by a spring 24. The ratchet wheel contains ten teeth and is fixed rigidly to the end of a worm 19 journaled in suitable bearings. One side of this worm is housed by a casing 20 on a graduated scale on which are marked numbers. A rock shaft 21 is journaled in bearings beside the worm and parallel thereto and has a traversing 25 pointer 22 whose end is bent down and enters the groove of the worm so that as the worm turns the pointer is carried along in the spiral groove along the numbered scale and the rock shaft slides longitudinally in its 30 bearings. At the end of the worm on its periphery is formed a depression or cavity 26, Fig. 6, and when the pointer 19 reaches the cavity the pointer drops into it and allows a hammer 25 on an arm of the rock 35 shaft to strike the bell. It will be seen that at each printing movement of the carriage the ratchet wheel and worm are turned the distance of one tooth. To set the apparatus for printing a predetermined number of 40 labels, the rock shaft 21 is rocked to throw the pointer 22 out of the worm and the rock shaft is then slid longitudinally until the pointer is opposite the desired number. The pointer is then dropped into mesh with the 45 worm; then, as the ratchet wheel is intermittently turned by the oscillation of the type casing the pointer traverses the worm to the end and then dropping into the cavity 26, as seen in dotted lines in Fig. 6, announces the completion of the printing of the 50 requisite number of labels.

An important advantage of my invention is, that a quantity of labels may be inserted in a stack at one time and be printed neatly 55 and quickly at any desired spot, the label thus printed being removed to expose the next label below for the next impression. This is a great economy of labor over the old method of picking up a single label inserting 60 it in place, printing it and then removing it.

It is only necessary in my device to remove the top label after printing and this is done as follows: The call number and sizes are usually stamped upon one end of the label, as at the spaces marked y, and this end of the 70 stack of labels is held down by the press plate, leaving the other end free to be buckled up and lifted out above the end lip by the thumb and finger and then be pulled out from under the press plate without disturbing those underneath.

For the purposes of my invention it is important to secure perfect registration on each label, and as the stack of labels grow less the 80 point of printing on the label would gradually run off to one side owing to the circular swing of the printing carriage, if it were not for the fact that the standing flange or gage 4 is made to lean toward the printing carriage as seen in Figs. 1 and 4, which causes the 85 bottom label of the stack to be the same distance from the center of oscillation of the carriage as the top label.

My invention enables the operator to print exactly the number of labels desired and 90 saves the labor of printing by hand. It also saves the loss of mutilated or spoiled labels which might otherwise be incorrectly printed or blurred, and it also acts as a check on the packing and shipping department.

In making use of my invention, I do not limit myself to the exact form of type holder, as these and other details may be varied without departing from my invention.

I claim:

1. A label printing device, comprising a base A, a parallel motion type-carrier mounted thereon and having two swinging links on each side and a base B mounted on the base A and provided with means for adjustment in two directions, a label holder arranged on the base B beside said type carrier and an ink pad arranged on the base A on the other side, of the type carrier.

2. A label printing device, comprising a 110 sub-base A, a swinging type carrier mounted on the middle of the same, a superposed base B mounted on the end of the sub-base and provided with means for adjustment in two directions, and a label holder arranged on the superposed base within the limits of the 115 swing of the type carrier.

3. A label printing device, comprising a sub-base A, a parallel motion type carrier having a slot, a type bed having a screw 120 threaded stem extended through the slot of the carrier, a screw threaded handle turned upon said threaded stem above the type carrier and adjustably clamping the type bed, a base B mounted on and adjustable in relation 125 to the sub-base and bearing a label holder arranged beside and adapted to register with the type carrier.

4. A label printing device, comprising a 130 sub base A, a swinging type carrier mounted

thereon, a holder for holding a stack of labels while being printed, consisting of a plate having at one end an adjustable overhanging lip for the ends of the labels, an elastic 5 presser for pressing down upon the other end of the stack of labels, and an adjustable gage plate at the side and a base B for said label holder adjustably mounted on the sub base.

10 5. In a label printing device, the combination with an oscillating type carrier; of a

label holder arranged beside the type carrier and adapted to hold a stack of labels, said label holder having a gage plate arranged to adjust the stack of labels to the circular 15 swing of the type carrier to insure continued and accurate registration as the labels of the stack are successively printed and removed.

ARTHUR LOW PATTERSON.
